COMPACT LUMINAIRE

George R. Hartz, Canoga Park, and Arnold S. Wasserman, Santa Barbara, Calif., assignors to Berkey-Colortran, Inc., Burbank, Calif.

Filed Oct. 24, 1972, Ser. No. 299,721

Term of patent 14 years

Int. Cl. D26—03

U.S. Cl. D48—20 K

FIG. 1.

FIG. 2.

FIG. 3.

FIG. 4.

FIG. 5.

FIG. 6.

FIG. 1 is a top plan view of a compact luminaire, incorporating our new design.

FIG. 2 is a front elevational view thereof.

FIG. 3 is a left side elevational view thereof.

FIG. 4 is a right side elevational view thereof.

FIG. 5 is a rear elevational view thereof.

FIG. 6 is a bottom plan view thereof.

The apertures are partially shown on the rear of the luminaire for convenience of illustration, it being understood that they are uniformly continuous over the area indicated.

We claim:

The ornamental design for a compact luminaire, substantially as shown and described.
